UNITED STATES PATENT OFFICE.

FRED WEINBERG, OF SCHENECTADY, NEW YORK.

TOY.

Application filed April 14, 1922. Serial No. 552,606.

To all whom it may concern:

Be it known that I, FRED WEINBERG, a citizen of the United States, residing at Schenectady, New York, in the county of 5 Schenectady, have invented certain new and useful Improvements in Toys, of which the following is a specification.

The present invention relates to toys of the wheel type intended to be rolled over 10 a floor as by being pushed or pulled by a handle and has for its object to provide an improved toy of this type which is attractive and entertaining to children, can be manufactured at a low cost, and is of a strong, 15 rugged character so as not to be easily broken.

For a consideration of what I believe to be novel and my invention, attention is directed to the accompanying description and the 20 claims appended thereto.

In the drawing wherein I have illustrated an embodiment of my invention, Fig. 1 is a side elevation of a complete toy; Fig. 2 is a side view of the toy with one side plate 25 or side piece removed, and Fig. 3 is a transverse vertical section.

Referring to the drawing, the toy comprises two round side plates or side pieces 5 and 6 fastened together at their centers by 30 a pin or spindle 7 to form a wheel adapted to be rolled over a flat surface such as a floor. The side pieces may be made from sheet metal, wood or other suitable material and are shaped so that when fastened together they resemble a wheel. They are 35 preferably made solid and are provided with embossed surfaces or colorations as indicated at 8 in Fig. 1 to represent spokes of a wheel. It will be understood that various 40 contours and colors may be used to give the desired pleasing appearance to the exterior of the wheel.

The side plates 5 and 6 are spaced apart to provide a chamber 9 and at the periphery 45 are inwardly curved flanges 10 and 11 which are spaced slightly apart so as to leave an annular slot 12 which communicates with chamber 9. The side plates may be maintained in spaced relation to each other by 50 suitable spacing means such as the hub members and washers indicated at 13 and 14 and they may be held by nuts 15 screwed onto the ends of spindle 7.

Pivots mounted between side plates 5 and 6 are one or more figures 16, three 55 being shown in the present instance. These

figures may take various forms, horses bearing riders being shown by way of example, the lower ends of the figures comprising triangular plates 17. The figures may be 60 made from suitable material such as thin metal and are weighted or counterbalanced at their lower ends by weights 18 so they tend to stand in an upright position. When in an upright position at the top of the wheel 65 the upper ends of the figures project through slot 12 beyond the periphery of the wheel. The pivots may comprise pins 19 fixed to the inner surface of one of the side plates. The pivot pins 19 are located at such a distance 70 from the periphery of the wheel and pass through the figures at such a distance from their lower ends that when the wheel rolls, the weights 18 strike flanges 10 and 11 just as the entire figures passes within 75 the confines of the wheel. This prevents the figures from turning entirely around on their pivots and serves to keep them within the confines of the wheel while they are passing beneath the center of the wheel. Refer- 80

ring particularly to Fig. 2, the top figure 16 is standing vertical with its upper portion projecting beyond the periphery of the wheel. If now the wheel is turned in a clockwise direction, as this top figure moves 85 beyond the vertical axis of the wheel it will swing on its pivot 19 in an anti-clockwise direction, gradually moving within the confines of the wheel and shortly after its pivot pin passes below the horizontal axis the 90 figure will have moved entirely within the chamber 9. The right hand Figure 16 in Fig. 2 is in a position where it is almost entirely in chamber 9. When entirely in chamber 9, the weight 18 at the bottom of the 95 figure strikes flanges 10 and 11 and so holds the figure from turning further. As the wheel continues to turn the figure remains stationary as it rides beneath the axis of the wheel and up the rear side, occupying 100 a position as shown by the left hand figure in Fig. 2. It remains in this position until the wheel in turning brings the center line through pivot 19 and counterweight 18 beyond the vertical when the counterweight 105 will swing the figure in a clockwise direction to quickly project the upper end of it through slot 12. The figure thus appears to jump from between the side plates. It will thus be seen that as the wheel rolls along 110 or turns on its axis each figure will successively disappear on the forward side of the

wheel and reappear on the rear side, riding in full view while at the top of the wheel. The figures are so proportioned and arranged that they never overlap so they can-
5 not interfere with each other and since they are within the confines of the wheel when passing beneath the axis of the wheel they cannot at that time be injured by contact with the surface on which the wheel is being
10 rolled.

I have described the operation of the figures with the wheel rolling or turning in a clockwise direction. The figures will appear and disappear in the same manner, 15 however, when the wheel is turned in the opposite direction. In other words, the wheel may be turned either way with exactly the same results. This feature of my structure is one of particular utility since
20 no attention need be paid to the direction of rotation and no injury can result from turning the wheel either way. That the device is adapted to operate when turned in either direction results from the fact that
25 the figures 16 are so pivoted that when turned in either direction from a vertical position as shown at the top of Fig. 2, they can move inside the confines of the wheel and are then prevented from further move-
30 ment by flanges 10 and 11 which form in substance stops for limiting the turning of the figures. This arrangement also provides for the quick projection of the figures from between the side plates and enables me to
35 use comparatively large figures for a given wheel diameter.

The toy may be propelled by a handle 20 having forked arms 21 provided with in-turned ends which enter sockets 22 in the 40 ends of pin 7, or by any other suitable means.

It will of course be understood that the wheel may be made of various diameters and that the figures may be of any desired char-
45 acter and counterbalanced in any desired manner. The figures may be as elaborate as desired and of any suitable color or colors. The structure comprises few parts of a shape easily manufactured in quantities and
50 the assembling is simple and can be done by relatively unskilled help. This means that the toy can be manufactured at a low cost.

In accordance with the provisions of the 55 patent statutes, I have described the principle of operation of my invention together with the apparatus which I now consider to represent the best embodiment thereof, but I desire to have it understood, that the apparatus shown is only illustrative and that the invention may be carried out by other means.

What I claim as new and desire to secure by Letters Patent of the United States, is:—

65 1. In a toy, the combination of spaced side

plates adapted to be rotated, a counterbalanced figure of lesser dimensions than the side plates pivoted in the space between them to one side of the center of the plates, the pivot for the figure being eccentric of 70 the figure and sufficiently close to the periphery of the plates that in one position the figure projects partly beyond the periphery of the plates, and stop means which prevents said figure from turning on its pivot 75 beyond a predetermined amount.

2. In a toy, a wheel member, a counterbalanced figure pivoted on a side wall of the wheel member, the pivot for the figure being eccentric of the figure and sufficiently 80 close to the periphery of the wheel member that in one position the figure projects at least partly beyond the periphery of the wheel member and that when turned on its pivot through an angle of less than 180 degrees in either direction it moves entirely within the confines of the wheel member, and stop means which limits the turning movement of the figure in both directions.

3. In a toy, a wheel having an annular 85 chamber between its sides and a slot in its periphery which communicates with the chamber, a plurality of figures pivoted within the chambers, the pivots for the figures being eccentric of the figures and sufficiently 90 close to the periphery of the wheel that when turned on their pivots they are projected through said slot, means connected to said figures for turning them on their pivots, and stop means which limits the 100 turning movements of said figures.

4. In a toy, a wheel member, a counterbalanced figure pivoted on a side wall of the wheel member and so located that when vertical it projects beyond the periphery of 105 the wheel member and when turned on its pivot through an angle of less than 180 degrees in either direction it moves entirely within the confines of the wheel member, a flange on the wheel member, and a part 110 on said figure which engages said flange to limit the turning movement of the figure in both directions.

5. In combination, a pair of complemen-
115 tary, flanged plates, means fastening them together at their centers in spaced relation to each other so as to leave a slot between the flanges, and one or more figures pivoted between said plates, said pivots being eccen-
120 tric of the figures and spaced sufficiently close to the periphery of the plates that when the plates are turned the figures will be projected through said slot when ap-
125 proaching a point over the axis of the plates, said figures having parts which engage said flanges to limit the turning movements of the figures on their pivots.

In witness whereof, I have hereunto set my hand this 11th day of April, 1922.

FRED WEINBERG.
